BATTING TRAINER

Norman J. Van Skyhawk, Salt Lake City, Utah, assignor
to Harmon Killebrew Enterprises, Inc., Salt Lake City,
Utah

Filed June 17, 1969, Ser. No. 17,748

Term of patent 14 years

Int. Cl. D21—
U.S. Cl. D34—5

FIGURE 1 is an enlarged perspective view of a batting trainer embodying my new design;

FIGURE 2 is a fragmentary side elevation view of the batting trainer of FIGURE 1;

FIGURE 3 is a front elevation view of the batting trainer of FIGURE 1;

FIGURE 4 is a rear elevation view of the batting trainer of FIGURE 1;

FIGURE 5 is a fragmentary top plan view of the batting trainer of FIGURE 1; and

FIGURE 6 is a fragmentary bottom plan view of the batting trainer of FIGURE 1.

I claim:

The ornamental design for a batting trainer, substantially as shown.
